(57) **CLAIM**

The ornamental design for a vehicle-shaped backpack, as shown and described.

DESCRIPTION

FIG. 1 is a rear, right perspective view of a vehicle-shaped backpack in the shape of a military vehicle showing my new design;

FIG. 2 is a right side view thereof, the left side view being a mirror image thereof;

FIG. 3 is a front elevational view thereof;

FIG. 4 is a top plan view thereof; and,

FIG. 5 is a rear elevational view thereof.

The broken line showing in FIGS. 1, 2, 3, 4 and 5 forms no part of the claimed invention. The straps, the vehicle shaped backpack bottom and the wheel thickness are not claimed.

1 Claim, 3 Drawing Sheets

FIG.1

FIG.4
